UNITED STATES PATENT OFFICE.

ANDREW HOWARD, OF BEAVER FALLS, PENNSYLVANIA.

DESIGN FOR A LAMP-SHADE.

SPECIFICATION forming part of Design No. 20,651, dated March 31, 1891.

Application filed January 22, 1891. Serial No. 378,706. Term of patent 3½ years.

To all whom it may concern:

Be it known that I, ANDREW HOWARD, a citizen of the United States, residing at Beaver Falls, in the county of Beaver and State of Pennsylvania, have invented a certain new and useful Design for Lamp-Shades; and I do hereby declare the following to be a full, clear, and exact description of the invention, reference being had to the accompanying drawings, which form part of this specification.

My design relates to the form and configuration of electric light and other shades; and it consists of a bell-shaped shade ornamented exteriorly with a series of prismatic projections or ribs arranged side by side and conforming in curvature to the shape of the shade.

In the accompanying drawings, Figure 1 is

a side view of a bell-shaped shade embodying my design. Fig. 2 is a horizontal sectional view of the same.

A designates the prismatic projections, which in cross-section have flat sides converging toward the sharp exterior edges a a and meeting at the sharp inner angles a' a' .

Having described my invention, I claim—

The design for a shade, substantially as shown and described.

In testimony that I claim the foregoing I have hereunto set my hand this 9th day of December, 1890.

ANDW. HOWARD.
